Fig.5

The undisclosed side of the receptacle is the same as the side shown in FIGURE 1.

The rear of the receptacle is essentially plain, as is its bottom.

I claim:

The ornamental design for an ash receptacle, as shown and described.
